UNITED STATES PATENT OFFICE.

ALEXANDER VAN VLECK, OF JORDAN, NEW YORK.

IMPROVEMENT IN CUTTER-HEADS.

Specification forming part of Letters Patent No. 123,800, dated February 20, 1872.

To all whom it may concern:

Be it known that I, ALEXANDER VAN VLECK, of Jordan, in the county of Onondaga and State of New York, have invented a new and useful Improvement in Matching-Cutters; and I do hereby declare that the following is a full, clear, and exact description thereof, which will enable others to make and use the same, reference being had to the accompanying drawing forming part of this specification, in which—

Figure 1 is an end view of a cutter-head having my improved cutters. Fig. 2 is a side view of a tonguing tool, and Figs. 3 and 4 are front and rear views of the same. Fig. 5 is a side view of the grooving-cutter, and Figs. 6 and 7 are front and rear views of the same.

Similar letters of reference indicate like parts in the several figures.

This invention relates to a kind of matching-cutters that may be described as follows: The cutters are made each of one piece of metal, with a straight shank for the cutter-head, and an outer portion or curve, so shaped that flat grinding of the face of the tool on a line with its heel gives always the same outline of cutting-edge necessary to make a tongue or groove, the outside of one of the projecting curved parts having a groove that makes the tongue, and the same part of the tonguing tool having a reverse form or rib. The invention consists in an improved construction or form of these blanks or curved portions from which the cutting-edge or outline is ground, by which the tools make a cleaner cut, and are run with less resistance, as hereinafter more fully described. The cutter for making the tongue is shown by Figs. 2, 3, and 4, A being the projecting curved portion and *a* the shank.

The curved portion of the tool has a channel or groove, B, in its rear side, for making the tongue, and the sides of this groove are made concave, as shown at *b*, to give the tool clearance, by which it makes a cleaner cut, is less liable to splinter the stuff, and cuts more freely through knots. The grooving-tool is the same in general form, the projecting portion having the same curve as shown by C, but is made with a rib, D, on its rear side, that forms the groove-cutting part of the tool. The sides of this rib are also made concave, as shown at *d*. The projecting portion can be all worn out down to the shank, and the tool always retain the same outline of cutting-face by grinding its face in line with the heel of the tool. With a chuck specially designed for the purpose, they are grooved and fitted up rapidly, and with a small expenditure of labor. By these means the cutters do the work in a superior manner, and from the improved clearance run easier.

I do not claim the construction of the cutters with a straight shank and curved cutting portion, as this is not original with me; but

Having thus described my invention, what I claim, and desire to secure by Letters Patent, is—

The herein-described improvement in matching-cutters, consisting of grooves *b* *d* in the cutting portions, substantially as set forth, for the purpose specified.

The above specification of my invention signed by me this 21st day of August, 1871.

ALEX. VAN VLECK.
